UNITED STATES PATENT OFFICE.

BENJAMIN BROIDO, OF NEW YORK, N. Y., ASSIGNOR TO THE SUPERHEATER COMPANY, OF NEW YORK, N. Y.

SUPERHEATER.

Application filed September 1, 1922. Serial No. 585,693.

The invention has for its object the provision of a superheater for steam in which the degree to which the steam is superheated is readily controlled and varied, and which 5 possesses certain other advantages which will appear as the description proceeds.

My invention is illustrated in the accompanying drawings, in which Fig. 1 shows a longitudinal section of a boiler and super- 10 heater embodying the invention; Fig. 2 is a section on line 2—2 of Fig. 1; Fig. 3 is an elevation looking toward the back of the boiler; Fig. 4 is an enlarged detail view of a portion of Fig. 2; Fig. 5 is a view similar 15 to Fig. 4, illustrating a modification; Fig. 6 is a section on line 6—6 of Fig. 4; and Fig. 7 is a fragmentary sectional view illustrating a modification. Throughout the views portions have been broken away when this 20 would not impair clearness.

For purposes of illustration I show my invention applied to a superheater used in connection with a boiler of a certain type; but it will be understood that it is in no way 25 confined to such a boiler, and may likewise be used in a superheater which is separately fired and not associated with any boiler.

Of the boiler there are shown in Fig. 1 only such parts as are required to make clear 30 its relation to the superheater. The water tubes 1 connect front and rear headers 2, 3. Hot gases from furnace 4 travel on their way toward the stack through the opening between the end of baffle 5 and the rear 35 header 3. Steam generated in the boiler is led from the drum (not shown) by pipe 6 to the upper header 7 of the superheater. This header 7 has secured to it the series of 40 superheater pipes 8 whose other ends connect with lower superheater header 9, from the end 10 of which the steam is led to the point of use.

The superheater pipes 8 bear over half the areas of their straight portions against the 45 plate 11, which is made of cast iron or other suitable material and is provided with semi-cylindrical grooves to accommodate the pipes. To keep the pipes 8 in engagement with the plate 11 there are provided the 50 bars 12. In the form shown there are nine such bars 12, but obviously the bars may be made longer or shorter, or spaced wider or closer, to suit conditions. Each bar 12 is forced against the pipes 8 by means of a 55 series of screws 13 screwed through threaded

holes in beams 14, which rest on supports 15 and abut against stops 16 of these supports.

In the face of plate 11 opposite the super- 60 heater pipes 8 there is a series of undercut grooves 17 which are fitted with refractory material 18.

The plate 11 is preferably made in sections, three such sections being shown corresponding to the three vertical rows of bars 12. This is again a matter of choice and 65 may be varied to suit circumstances.

In the operation of the device, steam flowing through the superheater is superheated in its course through pipes 8 by heat transmitted by plates 11 from the hot furnace gases 70 striking these plates on their furnace side and by radiation from the fuel bed itself. The maximum amount of heat is absorbed by the tubes when they are held in intimate contact along their entire length with plates 75 11 by the screws 13. If it is desired to obtain less superheat some or all of screws 13 are slackened, so that the contact of tubes 8 with plates 11 becomes less intimate. The precise change in the contact that occurs in 80 any given case may be very difficult to determine, as with such a slackening of the screws large separated areas may remain in contact or the areas remaining in contact may be 85 minute and spread more uniformly over the entire area. In any case the total area in contact will probably be smaller than before the set screws are slackened. A very slight slackening results in a large diminution of 90 the rate of heat transfer.

The refractory material 18 makes possible an additional control of the degree of superheat obtained. It acts as a partial protection against the heat of the furnace gases 95 and the hot fuel bed and by omitting or removing the material from some of the grooves or portions of all of them, the heat transfer through plates 11 is increased. This is a more permanent adjustment as it can be made only while there is no fire in 100 the furnace while the adjustment first described can be made with the boiler in service and with very little trouble.

The modification of Fig. 5 consists in further protecting plates 11 by extending 105 the refractory material 18 into portions beyond the grooves 17. The regulation by omitting the material from some grooves is possible in this case as in the other.

In the forms so far described the heat 110

- transmitted by plate 11 is received by it on one side and given up on the opposite side. Under some conditions an arrangement may be advisable in which heat is absorbed by one portion of one of the faces of the plate, transmitted along by the plate by conduction, and given up to pipes in contact with another portion of the same face. Such an arrangement is shown in Fig. 7.
10. The plate 11 here receives heat along the portion of the inner face below the partition 25, the source of heat being a furnace (not shown); the heat is conducted by the plate to the portion above the partition; and is absorbed by the pipes 8. The partition 25 and the pipes may obviously be arranged vertically or horizontally or at some other angle, without departing from the underlying idea.
20. The details of my invention may evidently be readily varied. The grooves need not have the precise shape shown; somewhat different means of forcing the pipes 8 into the semi-cylindrical grooves could be used; and other variations could be introduced. Moreover, while the invention is shown and described in connection with a superheater it can equally well be used in apparatus for heating a fluid other than steam, such as air, or water, or oil.
- What I claim is:—
1. In apparatus of the class described the combination of a pipe conveying a fluid to be heated, heat-conducting means adjacent to the pipe, means to supply heat to the heat-conducting means on the side away from the pipe, and means to exert variable pressure against said pipe in a direction to force it against heat-conducting means.
2. In apparatus of the class described the combination of a pipe conveying a fluid to be heated, a heat-conducting plate having a groove adapted to receive said pipe, means to supply heat to the plate on the side away from the pipe, and means to exert variable pressure against said pipe in a direction to force it into the groove.
3. In apparatus of the class described the combination of a pipe conveying a fluid to be heated, heat-conducting means adjacent to the pipe, means to supply heat to the heat-conducting means, and means to exert a variable pressure against the pipe in a direction to force it against the heat-conducting means.
4. In apparatus of the class described the combination of a plurality of pipes conveying fluid to be heated, a heat-conducting plate provided with grooves adapted to receive said pipes, means to supply heat to

the plate on the side away from the pipes, and means to exert variable pressure against the pipes in a direction to force them into the grooves.

5. In apparatus of the class described the combination of a plurality of parallel aligned pipes, a heat-conducting plate provided with semi-cylindrical grooves adapted to receive the pipes, means to heat the plate on the side away from the pipes, a bar engaging the pipes, and means to force the bar against the pipes with a varying degree of pressure.

6. In apparatus of the class described the combination of a heat-transmitting plate, a source of heat imparting heat to one face of the plate, protective material of low heat conductivity shielding a portion of said face from the source of heat, a plurality of fluid-conveying pipes adjacent to the opposite face of the plate, and securing means to force the plate and the pipes into contact, the arrangement being such that the closeness of the contact depends on the force applied to the securing means.

7. In apparatus of the class described the combination of a heat-transmitting plate, a source of heat imparting heat to one face of the plate, there being channels in said face, readily removable protective material of low heat conductivity shielding said face from the source of heat and comprising portions filling said channels, a plurality of fluid-conveying pipes adjacent to the opposite face of the plate, and means to press said pipes against the plate with variable force.

8. In apparatus of the class described, the combination of a pipe conveying a fluid to be heated, heat-conducting means held in contact with the pipe by pressure, and means to vary the extent of the surface of contact between the pipe and the heat-conducting means by varying the amount of pressure.

9. In apparatus of the class described, the combination of a heat-transmitting plate, a source of heat on one side of the plate, protective material of low heat-conductivity shielding a portion of said side of the plate from the source of heat, the plate being recessed on the side away from the source of heat, a plurality of fluid-conveying pipes engaging said recesses, a backing plate in contact with the pipes on the side away from the recesses, and securing means to force said plates toward each other and thereby to force the pipes into the recesses.

BENJAMIN BRODIO.
